MESSAGE TRANSMISSION DEVICE

Edward H. Hebern, Oakland, Calif., assignor to
 International Code Machine Company, Reno,
 Nev., a corporation of Nevada

Application November 8, 1938, Serial No. 239,469

8 Claims. (Cl. 178—22)

The invention relates to a remote control system in which differentiated electrical impulses of a like nature and representing different functions to be performed are produced and sent from a sending station to a receiving station for selectively causing the performance of the different functions.

A general object of the invention is to provide a remote control for a plurality of functions by single impulses representing the different functions.

A more specific object is to provide a remote control system which is particularly adaptable for the transmission of language messages and the printing of the same at the receiving station.

Another object is to provide for the transmission of a message at a rate considerably greater than that directly possible for a typist.

Yet another object is to provide a control system such that the transmission of control impulses and/or a message may be in code.

The invention possesses other objects and features of advantage, some of which, with the foregoing, will be set forth or be apparent in the following description of a typical embodiment thereof, and in the accompanying drawings, in which,

Figure 1 is a plan view of a sending unit for use in the system.

Figure 2 is a side perspective of a rotary impulse control element of the unit.

Figure 3 is a fragmentary sectional elevation at 3—3 in Figure 1.

Figure 4 is a front elevation of the unit of Figure 1.

Figure 5 is a fragmentary rear elevation of the mechanism of the unit.

Figures 6 to 9 inclusive are sectional elevations at 6—6, 7—7, 8—8 and 9—9 in Figure 1.

Figure 10 is a sectional elevation at 10—10 in Figure 5.

Figure 11 is an enlarged perspective and fragmentary view showing the mechanical control for the output switch of the sending unit and the circuit of the switch.

Figure 12 is a diagrammatic view of the mechanism and electric circuits of a receiving unit for reconverting the transmitted impulses into functions.

Figure 13 is a plan view of the receiving unit of Figure 12, a printing machine associated therewith being shown fragmentarily.

Figure 14 is a fragmentary elevation of the printing machine.

Figure 15 is a front elevation of the receiving unit of Figure 12.

Figure 16 is a right-end view of the receiving unit.

Figure 17 is a reverse-face view of an element of Figure 16.

5 Figure 18 is a fragmentary perspective showing of part of the mechanism in axial section, and a switch control device of the unit.

Figure 19 is a fragmentary and somewhat dia-grammatic view of the drive connections for the mechanism.

Figure 20 is a fragmentary rear perspective of the receiving unit.

Figure 21 is diagrammatic view showing an alternative receiving unit.

15 Figure 22 is a diagrammatic perspective of a tape-controlled unit for sending the function im-pulses.

Figure 22a is an enlarged fragmentary face view of a tape for use in the sending unit of Figure 22.

Figure 23 is a plan view of the unit of Figure 22.

Figure 24 is a partly sectional elevation of the unit.

25 Figure 25 is a sectional elevation at 25—25 in Figure 23.

Figure 26 is an elevation at 26—26 in Figure 24.

Figure 27 is an end elevation of the unit of Figure 22.

Figure 28 is a fragmentary plan view of a ma-chine for perforating a tape for its controlling use in the machine of Figures 22 to 27.

Figure 29 is an enlarged fragmentary section at 29—29 in Figure 28.

Figure 30 is a side elevation of the machine of Figure 28.

Figure 31 is an enlarged fragmentary sectional view at 31—31 in Figure 28.

40 Figure 32 is a generally diagrammatic show-ing of a system including the disclosed sending and receiving units and arranged for various use combinations, with and without coding ma-chines.

45 The disclosed apparatus for carrying out the present invention essentially includes a sending unit 21 which is operable to produce differentiated electrical impulses for wire or radio trans-mission to a receiving unit 121 which is con-trolled by the received impulses to cause the per-formance of any one of a number of different functions which are represented by the original impulses, the device thus constituting a remote control. The present apparatus has been partic-u-larly designed for the remote control of a print-

63

ing apparatus or typewriter P to reproduce and print out messages in accordance with an original message which is converted into a succession of significant impulses by the sending unit 21 which is operated in the manner of a typewriter. The present sending unit has a series of keys for selective operation to cause the emission of impulses which correspond to language characters or special operations of a printing mechanism to be controlled. Once a key of the sending unit 21 has been struck, the present apparatus automatically carries on to the performance of a desired function through the influence of the corresponding impulse on a receiving unit 121.

By particular reference to Figures 1 to 11 inclusive, it will be seen that the present embodiment of the sending unit 21 is carried on a base 22 and includes a constant-speed electric motor 23 for operating a speed-reducing drive gearing 24 thereof, together with fuses and suitable power connections for the motor. The mechanism for converting typewriter characters and operations into electric impulses is carried by a frame structure which comprises spaced and complementary end plates 25 and 26 fixed to the base 22 in opposed and mutually parallel relation and rigidly connected by a series of tie rods or bars 27, 28, 29 and 30 which are further utilized as will be brought out. A single-pole switch 31 is mounted on the outer side of the frame plate 25 and includes terminals 32 and 33 for connecting the switch in the output circuit for the unit.

Keybars 35 are pivotally and independently engaged with a common shaft 36 which is fixed in and between the frame plates 25 and 26 at a rearward point thereof adjacent the frame bottom, extend forwardly in generally horizontal position to a keyboard for the assembly, and carry usual keys 37 for selective engagement to depress the bars from their normal positions. As shown, twenty-eight keys 37 and corresponding keybars 35 are provided for producing impulses corresponding to the twenty-six letters of the English alphabet, a spacing of the letters between words, and a carriage return and line shift at the printer. The keys 37 are arranged in three banks or rows at different levels in a usual manner for typewriters.

Each keybar 35 comprises a flat strip of metal having an ear portion 38 extending radially downwardly of its pivotal axis at the shaft 36 and having its extremity connected with the frame bar 27 by a tension spring 39 which is constantly operative to urge a raised positioning of the keybar. The lower frame bars 27 and 30 mount similar plates 41 which respectively extend upwardly and downwardly from said frame bars and are slotted from their free edges to slidably receive the keybars in their slots as a guiding and positioning means for the individual keybars, the latter being evenly spaced apart along the keyboard. Means are preferably provided to prevent the depression of more than one keybar at a time; as shown, a laterally slotted angle plate 42 is mounted on the bar 27 for cooperation with the bar and the plate 41 thereon to provide an elongated space of uniform cross-section, said space being closed at its ends and containing a plurality of balls 43 of such diameter that only one keybar 35 may be depressed through their line at any time.

Members 44 are independently pivoted intermediate thereof on a common pivot shaft 45

which is mounted on and between the plates 25 and 26, said shaft being parallel to and in the same vertical plane with the shaft 36 on which the keybars 35 are pivoted. The members 44 are flat and are suitably retained in coplanar relation with the keybars as by the use of slotted plates 41 which are mounted on the upper frame bars 28 and 29 to respectively extend downwardly and upwardly from the bars and constantly receive the members 44 through their slots, it being noted that the plates 41 lie at opposite sides of the pivotal axis defined at the shaft 45.

Lateral extensions 46 of the keybars 35 extend upwardly to normally engage the lower edges of the forward portions of the members 44 and hold the portions of said members against the bar 28 as a stop means to limit the upward swinging of the keybars and members, the point of engagement of the extension and member preferably lying in a slot of the plate 41 on the frame bar 28, as is shown. A tension spring 47 connects each keybar 35 with the corresponding member 44 whereby the engagement of these elements is yieldingly urged and normally maintained.

A shaft 48 is journaled in and between the frame plates 25 and 26 in parallel relation to the shaft 45 and slightly below the members 44, and carries forwardly extending and mutually parallel arms 49 and 50 fixed thereto adjacent the inner faces of the plate. A bar 52 is fixed to and between the forward ends of the arms 49 and 50 for its normal and simultaneous engagement with and beneath all of the members 44 when the same are in their normal and simultaneous engagement with and beneath all of the members 44 when the same are in their normal raised position. It will be noted that the assembly of the shaft 48, and arms 49 and 50, and bar 52 provides a rock-frame 53, and that a depression of a keybar 35 is, through the action of the corresponding spring 47, arranged to resiliently and yieldingly urge a downward rocking of said rock-frame through the action of the corresponding member 44 on the bar 52.

An upward extension 49' of the arm 49 is arranged to effect the closing of the electric switch 31 when the frame 53 is sufficiently rocked in a manner hereinafter described. As shown, the extension 49' terminates in an ear 49'' which extends transversely and freely over the top edge of the plate 25 and engages beneath a spring arm 54 comprising the movable contact element 55 of the switch to normally dispose the contact point 55 of the element spaced from a fixed contact point 56 of the switch structure. A lever member 57 is intermediately pivoted on the plate 25 in generally horizontal disposition and with one end thereof engaged beneath the ear 49'' while the other end is pulled downwardly by a tension spring 58 engaged between the latter end and an anchorage on the plate 25, the lever 57 being arranged to constantly and yieldingly urge an upward swinging of the arm 49 to engage the bar 52 against all of the members 44.

It will now be noted that the possibility of lowering a member 44 sufficiently to effect a closing of the switch 31 when a key 37 is depressed is controlled by the rotatively adjusted position of a unitary rotary element 60 journaled in and between the frame plates 25 and 26. An axial spindle portion 61 of the element 60 carries weight discs 62 and 63 at its extending ends to increase the inertia of the assembly and

counterbalance the element 60 which may in itself be unbalanced with respect to its axis. The spindle 61 also carries a gear 65 by which the element is arranged to be controllably rotated from the motor 23 through suitable connections with the motor gear 24, said connections including a clutch means for intermittent engagement while the motor operates the gear 24 at a fixed and predetermined rotative speed.

As shown in Figures 2 and 3, the portion of the spindle 61 between the plates 25 and 26 carries a series of like tubular spacers 64 alternating with relatively thin and flat rings 66 which have outer portions thereof extend as flanges beyond the cylinder of the spacers, there being a flange 66 for each key 37 and the circles of the flange peripheries being of like radius. The bores of the spacers 64 and flange rings 66 are axially grooved for receiving a spline key which extends along and from the spindle 61 whereby the rings may be held against rotation about the spindle. The assembly of the members 64 and 65 is arranged to be clamped between sleeves 69 releasably set on the spindle adjacent the plates 25 and 26; as shown, the left-side 25 sleeve 69 threadedly carries a thrust ring 69' for adjustment to compress the members between the sleeves.

Rollers 67 are mounted on stub shafts which extend from corresponding intermediate points of the members 44, and the various flanges 66 are disposed in the planes of the rollers 67 for engagement by the different rollers, the axis of the element 60 being shown as disposed in a vertical plane through the common axial line of the raised rollers. Each of the flanges 66 is notched out longitudinally thereof whereby a cam action is provided with respect to a roller 67 which is free to follow the flange periphery. The flange notches 68 are all of different lengths and preferably start at the same axial line of the flange cylinder whereby all of the rollers 67 may simultaneously overlie an unnotched flange portion as a means to hold the switch 34 open.

Means are provided for rotating the element 60 through one revolution following the depression of any key 37, whereby, as the element rotates, the roller 67 of the member 44 which corresponds to that key may lower in the flange notch 68 by reason of the removal of the key bar extension 46 from beneath the front end of the member 44 and so permit a sufficient pulling down of the member against the bar 52 of the rock frame 53 to rock said frame and permit a closing of the switch 34 as long as the roller is disposed in the flange notch. It will thus be understood that a rotation of the element 60 while any key 37 is pressed down will result in a closing of the switch 34 for a definite period of time determined by the length of the notch 68 engaged by its corresponding roller 67, and that single electric impulses of different time length are produced as representing the different keys. It will be understood that the present structure of the element 60 is the operative equivalent of a cylindrical drum having a V-shaped depression cut in its surface longitudinally thereof with one radial side of the depression extending axially of the drum and its other side extending spirally of the drum, or a cylindrical drum having arcuate grooves cut in its surface to receive the rollers 67.

In the present instance, the flange notches 68 are of progressively greater lengths from left to right along the element, the notch representing

the letter Q being the shortest circumferentially of the roller and that representing the letter P being the longest. It will be understood, however, that the notches 68 of different length might have any one of a large number of random arrangements along the element whereby a transmitted message may be correctly reconverted or translated by a receiver only if the relation of the lengths of impulses to language characters is known for use in making appropriate connections at the receiver. As is hereinbefore brought out, the roller 60 is adapted for a rearrangement of the flanges, and the possible change of characters to electrical impulses of different lengths is therefore in itself understood to comprise a coding device with respect to a transmitted message. Furthermore, the keys 37 may be actuated in accordance with a coded message whereby to increase the difficulty of decoding by an unauthorized person.

The present means for effecting a rotation of the element 60 to produce an electrical impulse of appropriate length each time a given key 37 is operated, includes a rock-frame 10 which is mounted beneath the keybars 35 and comprises arms 71 and 72 extending rigidly and forwardly from a shaft 73 journaled in the frame plates 25 and 26, and connected at their forward ends by a bar 74 which closely underlies the keybars 35 in such relation thereto that a full depression of any keybar against the bar 74 is arranged to rock the frame 10 and lift the free extremity of a rearward extension 72' of the arm 72.

A pivot pin 75 extends transversely from the free end of the extension 72' of the arm 72 through a slot in the plate 26 and mounts the lower end of an upright thrust bar 76 which is disposed opposite the outer face of the plate, the bar 76 being slidably held against the forward side of a stop pin 77 on the plate by means of a tension spring 78 which is coactive between it and an anchorage on the plate. An arm 79 is pivoted on the outer face of the frame plate 26 near the top of the plate in generally horizontal disposition and with its pivot point at its forward end, and is normally held downwardly against the stop pin 77 by means of a tension spring 79' which is cooperative between it and an anchorage on the plate.

The plate 26 is transversely slotted from its top edge to provide a guideway for an arm 82 which extends from a pivotal connection with the frame bar 29 over and beyond the free end of the arm 78 to overlie the top end of an upright arm 83 which is pivotally engaged with a support bracket 84 extending from a bottom point of the plate 26, said arms being arranged for a limited swinging in a common plane. Tension springs 84 and 85 respectively urge movements of the arms 82 and 83 downwardly and toward the plate 26.

It will now be noted that a shaft 86 is mounted in and between the frame plates 25 and 26 for a slight longitudinal shifting thereof, and carries a gear 87 which is arranged to constantly mesh with the gear 65 on the trunnion 61 of the element 60, and is of the same size as the latter gear. A gear 88 is mounted on the plate 25 for free rotation about the shaft 86 coaxially thereof and in a fixed plane, is disposed between the gear 87 and the plate, and constantly meshes with the motor drive gear 24.

The mutually opposed faces of the gears 87 and 88 mount complementary clutch plates 87' and 88' respectively for mutual engagement to com-

plete a driving connection between the gears 24 and 65. Since the axial movement of the shaft 86 toward the motor will disengage the clutch plate 87' thereon from the other clutch plate 88', means are provided to constantly and yieldingly urge an engagement of the clutch plates, and other means are provided to permit such engagement only while the element 60 is to be rotated. As is particularly shown in Figures 1 and 5, an helical spring 89 freely receives the shaft 86 and is compressedly seated between a collar member 90 adjustably fixed on the shaft and a sleeve 91 freely receiving the shaft and reactive with the plate 25 through an anti-friction bearing 92, whereby to urge an engaged condition of the clutch while permitting a rotation of the spring with the shaft.

At the end thereof which extends beyond the frame plate 26, the shaft 86 carries a disc 93, and a roller 94 mounted on the arm 83 constantly engages the outer face 93' of the disc 93 in a circular line adjacent its outer edge, a portion of the otherwise flat disc face 93' being depressed in said line whereby the disc is operative as a face cam with respect to the roller 94 and the arm 83 which carries it. The under edge of the arm 82 is formed to provide an inwardly directed shoulder 95 which normally engages the outer end of the arm 83 to prevent an outward swinging of the latter arm from its normal upright position. When the arm 83 is secured by the shoulder 95 and the roller 94 engages the depression of the cam disc 93, the clutch plate 87' may engage the clutch plate 88', but when the shaft 86 is rotated to dispose the undepressed portion of the disc face against the roller the latter is reactive with the disc to shift the shaft 86 axially for disengaging the clutch to free the shaft and element 60 from the motor.

Since an actuated key 37 may be held depressed after its signal cycle is completed, means are preferably provided for automatically insuring a normal resecuring of the arm 83 by the shoulder 95 on the arm 82 independently of the key position and before a rotative cycle of the shaft 86 is completed. For this purpose, the lower edge of the arm 79 is cut away forwardly of its lower bearing face 86 which is engageable with the stop pin 77 and the upper end of the thrust bar 76 from a point slightly forwardly of the pin 77. The arrangement is such that the bar 76 may engage the face 80 while in contact with the side of the pin 77, yet may not engage the arm 79 at all if it is swung forwardly from its pin-engaging position. For rendering the bar 76 inoperative with respect to the arm 79, a cam projection 96 is provided on the shaft 86 for engaging the bar 76 to deflect it to an inoperative position with respect to the arm 79 before the roller 94 engages the depression of the cam disc 93 to release the clutch; in this manner, the arm 82 may descend to catch the top of the arm 83 behind the shoulder 95 while the roller engages the depression. As shown, the cam projection is provided as a pin extending from the hub portion of the cam disc 93.

When the present sending apparatus is in condition for sending therewith, the member 60 is arranged to be so set rotatively thereof that the rollers of the members 44 engage the unnotched portions of the flanges 68 of the member adjacent the advance ends of the notches 68, the shoulder 95 of the member 82 secures the arm 83, and the roller 94 on the latter arm engages the undepressed portion of the cam face 93' adjacent the

trailing end of the depression therein. With the motor energized and operating at a fixed speed, the depression of any key 37 frees the corresponding member 44 for its downward movement to permit a closing of the switch 34 in the described manner, and the rocking of the frame 70 simultaneously moves the thrust bar 76 upwardly to lift the arm 82 out of securing engagement with the arm 83 to free the latter to permit an engagement of the clutch and so set the shaft and element in rotation.

As the element 60 rotates, the roller 94 of the freed member 44 drops into the corresponding flange notch 68 to provide a timed closing of the output circuit including the switch 34. After the roller 94 has left the notch and again rides on the unnotched flange portion or is held clear of the flange by the returned keybar extension 46, the simultaneous rotation of the cam disc 93 is arranged to dispose the roller 94 in the depression of the cam disc 93 to provide for the resecuring of the member 83 and the disengagement of the clutch as the roller leaves the depression. As the clutch is disengaged, a friction element or detent 97 carried on a spring arm mounted on the base 22 engages a notch 98 in the periphery of the weight disc 63 for insuring a stopping of the rotary elements in their normal starting positions.

The control impulses produced by the sending unit 21 may be transmitted to a receiving unit 121 in any desired manner, as by wire or radio. The present device of producing electrical impulses of different time duration to represent different characters or functions lends itself particularly to radio transmission between sending and receiving stations, and such an arrangement is particularly indicated in Figures 11 and 12 wherein the output switch 34 is connected in series with a battery 101 and a suitable broadcasting unit 102 in which said impulses are amplified if necessary and are transformed into radio impulses of the same duration as the current impulses which give rise to them, all in a manner well known in the radio broadcasting art. The radio impulses from the broadcasting unit 102 are arranged for picking up to produce corresponding electric current impulses by a suitable radio receiver 103, said current impulses comprising the input to the receiving unit 121 for segregation thereby for operating the typewriter or printing device P for reproducing the original message or performing a predetermined function. It will be understood that the current output of the sending unit 21 may be sent to the receiving unit 121 directly by wire, with or without relay amplification, in lieu of by radio.

Essentially, the reconversion into function operations of the impulses transmitted from the sending unit 21 to the receiving unit 121 is effected by selectively energizing at the receiving station the appropriate one of a plurality of local circuits connected in parallel and each controlling the operation of the printing unit P for printing the character or performing some other operation which corresponds to the received impulse, the operation being automatically controlled by the received signal impulse itself. Each of said local circuits is controlled in part by a multiple switch of the commutator type whereof its movable contact element is rotated at the same rotative rate as is the element 60 of the unit 21 which controls the duration of the original control impulses, and successively closes branch circuits thereat which correspond to characters

or functions which are represented by impulses of progressively greater duration. A main switch controls all of the branch circuits and is automatically closed at the termination of an input impulse whereby to energize only the one branch circuit which corresponds to the duration of the impulse and is closed by the multiple switch.

The elements of the present receiving unit 121 are mounted on a common base 122 and include an electric motor 123 which is arranged to actuate a drive gear 124' of the motor assembly at a constant speed which may equal that for the sender motor 23. A major portion of the receiving mechanism is carried on a rigid frame structure which comprises spaced and complementary side plates 125 and 126 fixed to the base 122 and connected by spacer bars 127, and a front plate 128 extending from the base 122 and fixed at its top to the upper front bar 127. The base 123 further mounts fuses and suitable power input connections for the motor and the local circuits of the units, including a pair of contacts 129 for connecting the input circuit with the unit.

A shaft 131 is journalled in and between the frame plates 125 and 126 and extends somewhat beyond each of the plates. A flywheel disc 132 is mounted on the shaft extension nearest the motor, and the shaft also carries a gear 133 fixed thereto adjacent the disc 132. The other end of the shaft 131 extends through and beyond a fixed contact plate providing a central contact ring 135 which is continuous, and a line of equally spaced contacts 136 at its outer face and arranged in the arc of a circle which is concentric with the shaft. An arm 131 extends radially from the shaft opposite the outer face of the plate 134 and carries brushes 138 and 139 connected by a conductor 140, said brushes being respectively operative at the ring 135 and the contacts 136 whereby the arm may provide a bridging connection between the contact ring and the different contacts 136 as the arm is rotated. The contacts 136 are equally spaced in their line except for a gap which corresponds to a number of the contacts.

A counterweight 140 is mounted on the shaft portion between the plates 125 and 126 whereby the eccentric weight of the arm 137 may be counterbalanced. The plate 134 and arm 137 may be of a non-conducting material such as fibre or Bakelite, whereby to insulate the various contacts of each element from the shaft and from each other, and connections are provided for each of the contacts 135 and 136 at the back of the plate 134, as is brought out in Figure 16.

As shown, the brush arm 137 extends from the outer portion 141 of a cylindric sleeve which receives the shaft 131 and is clamped against the opposed end of an inner sleeve portion 141' by a thumbscrew 142 engaging axially in the shaft end, only the portion 141' being directly fixed to the shaft. The opposed faces of the sleeve sections 141 and 141' are corrugated or roughened for their frictionally locked engagement by the screw 142 whereby a release of the screw permits an adjustment of the arm 137 rotatively of the shaft. As will hereinafter be brought out, the normal disposition of the brush 139 of the arm 137 is at a certain point between the ends 70 of the arcuate line of contacts 136 while the shaft 131 is releasably retained in a set position by a detent means which is operative against the disc 132, and rotary adjustment of the arm 137 on the shaft may therefore be necessary for pro-

viding a properly coordinated operation of the mechanism, with reference to the sending unit which is to control its operation.

5 A shaft 143 is journalled in and between the frame ends 125 and 126 for both its rotation and a slight axial shifting thereof, and carries a gear 144 fixed thereto at its extremity nearest the motor for constant engagement with the gear 133 on the shaft 131, said gears being of like size whereby the shafts which respectively mount them may constantly have the same rotative positions and speeds. A gear 145 is mounted on the outer side of the plate 125 for free rotation about the axis of the shaft 143 in a fixed plane, and constantly meshes with the motor drive gear 124'. The mutually opposed faces of the gears 144 and 145 mount complementary clutch plates 144' and 145' respectively whereby to complete a driving connection between the gears 124' and 133 when the clutch plates are engaged.

20 Means are provided to constantly and yieldingly urge the shaft 143 axially thereof for maintaining the engagement of the clutch plates, and other means are provided to permit such engagement of the clutch plates only while the arm 131 and the shaft 143 are to be rotated. As shown, an helical spring 146 freely receives the shaft 143 and is compressedly seated between a collar member 147 adjustably mounted on the shaft and a sleeve 148 freely receiving the shaft and reactive with the plate 125 through an anti-friction bearing 149 for permitting the rotation of the spring with the shaft. It will be noted that the clutch connections for the shaft 143 are similar to those for the shaft 86 of the sending unit 21.

25 A lever member 151 having arms 152 and 153 extending oppositely in generally parallel relation to the base 122 and an arm 154 extending downwardly from its pivot point is pivotally mounted on the outer face of the frame plate 128 adjacent its top. A tension spring 154' is operative forwardly against the free end of the arm 154 to urge a rotation of the member 151 to a normal position in which the arm 153 engages a stop pin 155 extending from the plate 126. An arm 156 is pivoted to the upper and rear frame bar 127 for swinging on a plane transverse to the plate 126, said arm extending through and beyond a guide notch or slot provided in the top of the plate. The under edge of the arm 156 is normally held against the bottom of the slot to dispose its outer portion close to but out of contact with the top of an upright swingable arm 157 which extends from a pivot provided on a bracket mounted on the plate 126 near its bottom for swinging in the same plane with the arm 156, and closely overlies the arm 153 of the member 151. As shown, a downwardly directed lateral extension 156' of the arm 156 is engaged by one end of a tension spring 156'' which is operative between the free end of the arm 156' and an anchorage provided on the bar 127 which mounts the arm 156, whereby to yieldingly urge the engagement of the arm 156 against the slot bottom.

30 Intermediately thereof, the upright arm 157 carries a roller 159 which constantly and eccentrically engages the outer face 160 of a disc cam 161 fixed on the extremity of the shaft 143. A tension spring 157' is constantly operative between the arm 157 and an anchorage on the aforesaid bar 127 to urge a retention of the roller 159 against the cam face 160, but is not strong

enough to overcome the resistance of the spring 146 to effect the condition of the clutch device. The annular portion of the cam face 160 which is engaged by the roller 159 is flat except for one relatively short arcuate depression therein for receiving the roller during part of each rotative cycle of the cam and its shaft 143.

It will now be noted that the under edge of the arm 156 is stepped to provide a rearwardly directed shoulder 162 which normally engages the outer top corner of the arm 157 to positively limit the outward swinging thereof. When the arm 157 is held by the shoulder 162, the roller 159 thereon is arranged to forcibly engage the undepressed portion of the cam face 160 to hold the shaft 143 axially displaced for disengaging the described clutch device, the arrangement being similar to the control for the clutch of the sending machine 21. If, with the clutch engaged, the shaft 143 is rotated to permit the disposal of the roller in the cam depression, the arm 157 may swing inwardly to permit an operative disposal of the shoulder 162 for again securing the arm 157 following its release by raising the arm 156 to permit the engagement of the clutch and the rotation of the shaft.

The described mechanism for controlling the clutch is in a normal static condition when the brush 139 engages the contact plate 134 at the beforementioned intermediate point of the contact plate, the arm 157 is held by the shoulder 162, and the roller 159 engages the undepressed portion of the cam face 160 adjacent the trailing end of the cam depression to hold the clutch disengaged, this being the condition shown in the drawings.

Having the motor 124 operating continuously at a fixed predetermined speed, a pulling down of the forward arm 152 of the lever 151 is arranged to engage the rear arm 153 of the same member with the arm 156 to lift the latter to free the arm 157 for its outward swinging under the influence of the shaft spring 146 and permit the engagement of the clutch 144—145; the latter results in a simultaneous and like rotation of the shafts 131 and 143. Just after the brush 139 has completed its traverse of the line of contacts 136, the roller 159 is arranged to engage the depression of the cam face 160 and so provide for reengaging the arm 157 with the shoulder 162 as the continued rotation of the cam and shaft moves the roller out of the depression to release the clutch and permit a stopping of the mechanism in its original and normal condition.

It will now be noted that a roller 164 carried on a spring arm 165 extending from the base 122 constantly bears against the periphery of the disc 132 on the shaft 131 and is operative as a spring detent in a notch 165 of the disc edge when the disc is in its normal static position. The shaft 166 of the roller 164 is arranged for its engagement by the top edge of the rear arm 157 of a lever 168 which extends along the plate 125, is intermediately pivoted on said plate, and has its other arm 169 extend slightly forwardly of the front frame plate 128 and beneath the extremity of an arm 171 which is pivoted on the plate 128 in general parallelism to the base 122; the arms 167 and 169 are shown as extending from a common hub and in relatively offset position transversely thereof. A tension spring 171' is reactive with the arm 171 to urge its engagement with a stop pin 172 which extends beneath it from the plate 128, the pin 172 being so located that the inner end of the lever 168 is held close

to the roller shaft 166 when the pin is engaged by the arm 171.

A thrust bar 173 is carried by and extends upwardly from a pivotal connection with the arm 171 and is urged to normally retain a sliding engagement against a stop pin 174 which extends from the plate 128 through the action of a tension spring 173' which is reactive between it and the plate. The pin 174 is also normally engaged against the under side of an arm 175 of an horizontally disposed lever 176 having its other arm 177 engaged beneath a spring contact arm 178 of a switch 179, the arrangement being such that the contact 181 of the switch arm 178 is held away from the fixed complementary switch contact 182 when the lever arm 175 engages the pin 174, the latter being constantly urged by the action of a spring 176' which is operative against the lever 176 with a strength sufficient to overcome the resilient resistance of the switch arm 178 to a separation of the contacts 181 and 182 of the switch.

It will now be noted that the thrust bar 173 is provided at its upper end with a shoulder or seat 173'' which normally underlies the tip of the arm 175 of the lever 176 and is close to the latter when the arm engages the pin 174. Under these conditions, a raising of the bar 173 is arranged to engage its seat 173'' with the lever arm 175 to rock the lever 176 and permit a closing of the switch 179. If, however, the bar 173 should be swung away from the pin 174 before or while it is raised, it will be inoperative to engage the tip of the lever arm 175 and so may not then operate for raising the arm or holding it raised, the switch then being open as is normal. It will be understood that the displacement of the detent roller 164 while the disc 132 and other rotatable members are rotating during an operative cycle of the mechanism will act positively through the lever 168 and the arm 171 to lift the thrust bar 173 to its raised position during the displacement of said roller.

An electromagnet 183 is provided for energizing and actuation to rock the bar 173 to an inoperative relation to the switch control lever 176. As shown, the armature 183' of the electromagnet extends opposite and generally parallel to the bar 173 and has a pin 184 extending laterally therefrom into a longitudinal slot 185 provided in the upper bar and longitudinally of the bar. When a circuit which includes the solenoid 183'' of the electromagnet 183 is closed, the resulting movement of the armature 183' against the resistance of the spring 173' effects the inoperative disposal of the bar 173 as described. The arrangement is such that when the bar 173 is swung sufficiently away from the pin 174 while in elevated position, the opposed extremity of the lever 176 may engage its side to prevent its return movement while it is held raised, as is the case as long as the roller 164 is out of the notch 165 of the disc 132.

An electromagnetic means is provided for actuating the lever 151 to release the clutch for starting a cycle of operations of the mechanism. As shown, an electromagnet 186 is mounted on the base 123 beneath the forward end of the lever arm 152 and with its normally spring-raised armature 186' movable in a vertical plane in or adjacent the plane of movement of the arm. A link 187 connects the free end of the armature 186' with the free end of the lever arm 152, and the depression of the armature 186' on account of an energizing of the electromagnet solenoid

186" is arranged to actuate the lever 151 to provide for the described cycle of operations of the apparatus.

An electromagnetic two-way switch 188 is provided having its coil or solenoid 188" connected in series between the input contacts 129 by means of wires 222. The armature 188' of the switch 188 is a conductor and its free end is alternatively engageable with contacts 189 and 190 when the switch solenoid is deenergized and energized respectively. It will, of course, be necessary that the current input for the solenoid 188" be strong enough to effect a displacement of the armature from its normal engagement with the contact 189 to engage the contact 190 and against the resistance of a usual spring which normally holds the armature against the contact 189. As shown, the switch 188 is mounted on top of the frame of the described mechanism.

As is shown in Figures 12 and 13 and 22, the typewriter or printing machine P for remote control through the present system is provided with a set of keys 191 corresponding to the keys 37 of the sending unit 24 and carried on keybars 195. Said keybars are arranged for individual actuation electromagnetically by the energizing of electromagnet coils 192 having movable cores 193 normally extended and provided with hooks 194 which engage over the keybars of the various keys for rocking the keybars when their corresponding electromagnets are energized. The set of electromagnet assemblies may be provided as a part of the printing unit P, or as a separate key-operating unit K for the engagement of its solenoid-controlled hooks 194 with the keybars of the printer; in either event, the combination P—K is understood to comprise an electrically actuated printer or typewriter. It is to be understood that the unit P generally represents mechanisms adaptable to remote control such, for instance, as air and water craft, explosive mines, etc.

The circuits of the unit 121 derive their operating current from power input wires or conductors 198 and 199 which may also supply the power for the motor 124, as is indicated. As shown, a conductor wire 201 connects the armature switch arm 188' of the switch 188 with the power wire 198, a wire 202 connects the contact 190 of the switch 188 with one terminal of the solenoid 186", and a wire 203 connects the other terminal of the solenoid 186" with the power wire 199, said connections providing a normally open circuit which requires only the closing of the switch 188 at the contact 190 to energize the solenoid 186".

A wire 205 extends from the contact 189 of the two-way switch 188 to the contact ring 135 of the contact plate 134, wires 206 connect the different contacts 136 with one terminal of each of the different key-operating solenoids 192, and a common return wire 207 connects the other solenoid terminals with the arm contact 181 of the switch 179; the arrangement is understood to provide mutually parallel branch circuits between the ring 135 and the switch 179. The switch contact 182 is connected with a terminal of the solenoid 183" of the electromagnet 183 by a wire 208, and a wire 209 connects the other solenoid terminal with the power wire 199 to complete a selective control circuit for the functions to be performed, said circuit comprising in part an output circuit for the receiving unit 121.

By reference to Figures 13 and 15 and 18 and 21, it will be seen that the armature 183' is en-

gaged by a spring contact arm 211 of a switch 212 whereby to engage a contact of said arm with a complementary contact of a second spring arm 213 of the switch. The switch 212 is arranged for inclusion in a controlled circuit which is closed at the switch while the bar 173 is held away from the pin 172 by the energized electromagnet 183 and/or the lever 176. It will be noted that the switch 212 is held closed mechanically after the circuit of the switch 179 is reopened in each cycle of operations of the receiving unit whereby the function of its circuit is generally supplementary to the functions of the multiple circuits controlled by the commutator switch assembly 134, and endures until the cycle is terminated and the bar 173 is lowered to move away from the solenoid and so reopen the switch. The arrangement is understood to constitute a relay switch with respect to the circuit of the switch 212.

Having the various working parts of the present receiving unit 121 in the normal conditions described and shown for them, the motor 123 operating at the required speed, and the two mutually parallel circuits controlled by the switch 188 both open, an output current impulse from the radio receiver 103 is operative to energize the solenoid 188" to cause the engagement of the armature 188' with the contact 190 and so close the circuit of the electromagnet 186 to rock the lever 151 and initiate a cycle of operations of the mechanism by causing the engagement of the drive clutch. When the actuating impulse ceases, the armature 188' again engages the contact 189 to close therewith the circuit which includes the contact ring 135, the connected brushes on the contact arm 137, a contact 136 which is then engaged by the brush 139, a solenoid 192 connected with the engaged contact 136, the switch 179, and the solenoid of the electromagnet 183.

Referring particularly to the primary output circuit which includes the normally open switch 179, it will be noted that the displacement of the detent roller 164 to ride on the edge of the disc 132 during a rotation of the disc is arranged to lift the bar 173 to rock the lever 176 to permit a closing of the circuit at the switch 179. Assuming that the brush 139 is engaging a contact 136 when the input current ceases, the reengagement of the armature 188' of the switch 188 with the contact 189 provides a completely closed circuit through the electromagnet 192 whereby to actuate a keybar or other element of the printing mechanism which corresponds to the contact 136 in the circuit. This establishing of a current through the solenoid 183" of the electromagnet 183 results in an actuation of the armature 183' to pull the bar 173 from beneath the arm 175 of the lever 176 and so permit a swinging of the lever to engage the stop 172 and open the switch 179 by the action of the spring 176. It will be understood that there is a time lag between the energizing of the circuit and the opening of the switch 179 which is normally sufficient to permit the operative actuation of the hook 193 of the energized solenoid 192 before the switch is opened. Also, the movement of the brush 139 over the engaged contact 136 is so timed that the contact provided thereby will endure until the switch 179 is opened as described.

It will be understood that the closing of a function circuit through a solenoid 192 is jointly determined by the initiating and duration and termination of an input impulse to the coil of the

switch 188. Accordingly, the relay switch 216 will be held closed only for the balance of an operative cycle which was started by the impulse, whereby the time duration of the closing of said switch will vary inversely with the duration of the actuating impulse. As shown, a wire 215 leads from the power wire 198 to one terminal of a lamp 216, a wire 217 leads from the other lamp terminal to the arm 213 of the switch 212, and a wire 218 leads from the switch arm 211 to the other power wire 199 to provide a supplementary circuit for the lamp 216 which is lit as a telltale only after an electromagnet 192 has been energized and deenergized in a cycle; the supplementary circuit of the switch 212 may obviously control some other device, or devices than a lamp, however.

It will be understood that the rotative speed of the contact arm 137 of the receiving unit 121 must be so synchronized with the rotative speed of the impulse-timing element 60 of the sending unit 21 that the proper output circuit may be energized as the impulse ceases. For providing this relation, the rotative rates of the element 60 and arm 137 are, in the present instance, designed to be equal, this being accomplished by having the respective drive motors 23 and 123 comprise like alternating current synchronous motors which automatically operate at fixed speeds in terms of the frequency of alternations of the operating current. With the gearing connections the same for both motors, it is merely necessary to supply operating power thereto from alternating current sources of like frequency whereby the required synchronized operation of the sending and receiving units may be provided. Also, the first contact 136 which is engaged by the brush 139 on the contact arm 137 during a rotative cycle thereof must be reached by the brush from its starting position at rest in the time of the shortest signal impulse, and it will be recalled that the described provision for rotating the arm 137 on the shaft 131 permits this vital setting of the arm for its timed operation.

While the operation of the solenoids 192 may be sufficiently rapid to complete their work in the short time permitted by the operation of the unit 121, it has sometimes been found desirable to utilize the output current corresponding to a particular impulse to operate a relay switch which may maintain its secondary circuit for the time that the switch 212 is closed, and so insure the performance of a function which requires more power and/or time than is provided by the rotary contact device of the unit 121. Accordingly, and as shown in Figure 21, a receiving unit 219 is provided for energizing electromagnetic relays 220 in lieu of the solenoids 192 of the unit K for operating a printing machine or other mechanism to be controlled. The solenoids 221 of the said relays are connected with different contacts 136 by means of the wires 206 and with the switch 179 by the common conductor 207, and are arranged for the continued closing of the switches 222 of their secondary circuits until an impulse cycle is completed for the relay switch 220 thus provided, this arrangement essentially comprising a delayed action for the opening of the switch 212.

As is particularly shown, the relays 220 are of similar structure to the relay 183-212 of the unit 221, and their armatures are arranged for control with and in the same manner as the armature 182 of the first relay. The control lever 223 which carries a roller 164 at its inner end to

engage the notch 165 of the disc 132 in the described manner replaces the lever 188 and is part of a rock-frame 224 which fixedly carries a contact bar 225 at its forward end to engage beneath corresponding ends of a bank of similar levers 226 which correspond to the lever 171 and are rotatively pivoted on a fixedly mounted shaft 227. The bar 225 and shaft 227 are mutually parallel to each other and to the pivotal axis of the rock frame 225. One of the levers 226 carries a thrust bar 173 for control at the relay 183-212 as before, and the remaining levers 226 carry corresponding and similar thrust bars 228 for control as the bar 173 and with respect to the different relays 220.

A stop bar 229 extends opposite the members 173 and 228 adjacent their upper ends and at the opposite side thereof from the various relay armatures to which they are connected by pins 184 engaged in longitudinal slots at the bar ends, and springs 231 are normally operative to yieldingly hold the members against the bar 229. The latter bar is operative as the pin 172 of the unit 121, and when the members 173 and 228 are in lowered position, seats 183 of the members lie just below the top line of the bar. A lever 176 is operative at the bar 173 to control a fixedly mounted switch assembly 179 and the disposal of the bar with respect to the solenoid 183' in the previously described manner, and levers 232 are provided which correspond to the arms 175 of the lever 176 and are coactive with the various trust bars 228 in the same manner. Springs 233 are constantly operative to urge the levers 232 to engage the top of the stop bar 229. It will be understood that when an electromagnet 221 is energized, with the corresponding bar 228 raised, the latter bar is displaced to close its switch 222 and permit the engagement of the opposed end of the lever 232 against its outer edge to maintain a closed condition of the switch until the bar is lowered by the engagement of the roller 164 in the notch 165 of the disc 132. It will be understood that although all of the thrust bars 228 are held raised during an operative cycle of the commutator switch of the unit, only the switch 212 and one switch 222 will be closed during the cycle.

With the present unit 219 in its normal receiving condition, an output current impulse reaching the solenoid 188' through the wires 200 is operative to energize the solenoid to cause the closing of the switch at the contact 190 and so close the circuit of the electromagnet 188 to rock the lever 151 through the link 187 and so initiate a cycle of operations of the mechanism by causing an engagement of the drive clutch and the rotation of the arm 137. When the actuating impulse ceases, the armature 188' again engages the contact 186 to close thereat a circuit which includes the contact ring 135, the connected brushes on the arm 137, a contact 136 which is then engaged by the brush 139, the solenoid of a relay 220 corresponding to the engaged contact 136, the switch 179, and the solenoid of the electromagnet 183.

Since the engagement of the clutch has caused the rotation of the disc 132 to rock the lever 223 and so raise all of the thrust bars 173 and 228 to displace the arms 175 and 232 respectively, the energizing of the last aforesaid circuit will effect a displacement of the bar 173 and the bar 228 of the then energized relay switch to open the said circuit and close the working or function circuits of the switch 212 and the appropriate

switch 222. In this manner, the automatically selected function circuit 230 of a switch 222 will be held closed at its switch until the original quiescent status of the unit 219 is restored. The operations of the function circuits may be the control of a printing machine P, as with the electromagnets 192, the selective remote control of mechanical equipment or vehicles, the firing of guns or mines, and the actuation of other devices. It will be understood that a succession of function impulses in a particular and predetermined order may be required and utilized to cause the performance of a particular function; this may be termed a coded control.

Recalling that but a single impulse is required for production and transmission and translation by the present device to energize a given function circuit, it will be noted that the sending of impulses representing language characters is limited only by the speed of a typist rather than the slower speed per character of a telegraph or "teletype" operator, it being recalled that a plurality of mutually timed operations to represent a character must be effected in the latter instances. Also, the present device in no way involves the relative timing of successive impulses as required with the other mentioned devices, since each impulse of a succession of impulses is independent of every other for function-controlling purposes, its timing being related only to its own cycle of origin. It will therefore be understood that the sending of messages with the present apparatus may be several times as fast as by telegraph or "teletype," and has the further advantage of directly printing the transmitted characters and message.

Under some circumstances, as in wartime communication between spaced points, it may be desirable to transmit a message at a still greater speed than a typist may send it directly. As is shown in Figures 28 to 31, a unit 301 is provided to convert a typed message into perforations in a tape which may thereafter be run through the sending unit 241 shown in Figures 22 to 27 and arranged for actuation to provide the output impulses at a mechanically controlled speed which is very much higher than possible human speed; the present apparatus may effect the transmission and reconversion of the character impulses at the rate of six hundred or more per minute.

Aside from the coding which is directly possible through varying the significance of the impulses sent to the receiving units 121 or 219, the keys of the sending unit 21 or of the tape-marking unit 301 may be operated in terms of a coded message, or the latter units may be directly operated automatically from a cipher machine such as is described in my copending application Serial Number 232,995, filed October 3, 1938. When a cipher machine is used for sending a language message, the output circuit of the receiving unit 121 or 219 would have a corresponding deciphering machine operatively interposed between it and the printing machine P.

As is illustrated, the sending unit 241 is arranged for operation in accordance with a longitudinal line of perforations on a control tape 242 for effecting the emission of function impulses of variable length and corresponding to the impulses which may be sent out from the sending unit 31 which it may replace in a remote control system utilizing the receiving units 121 or 219. The successive tape perforations 243 are each variably spaced from each other along the tape to represent impulses of different

lengths, and reference perforations 244 may be provided along an edge of the tape. The perforations of the control tape 242 are provided by a suitable means such as the unit 301, and the tape may be of a material which permits its repetitive use.

As shown, the mechanism of the unit 241 is mounted on a base plate 245 which carries an electric motor 246 arranged to drive a gear 247 of its assembly at a predetermined speed, and suitable power connections including wires 248 and 249. A shaft 252 carries a gear 253 at one end thereof and in constant engagement with the motor gear 247, and is journaled in a bearing sleeve 254 which is fixed on a bracket plate 255 extending from the base 245. The shaft 252 is parallel to the shaft of the gear 249, and an anti-friction thrust bearing 256 is operatively engaged between the gear 253 and the opposed end of the sleeve 254.

The plate 255 mounts a single-pole switch 257 having a fixed contact 258, and a movable contact 259 of the switch is carried on a spring arm 261 which is normally spaced from the contact 258 to maintain an open condition of the switch. An arm 262 is fixed on and extends radially from the other end of the shaft 252, and said arm is operative for engaging the spring switch arm 261 once in each revolution of the shaft 252 to engage the contacts 259 with the contact 258 to close the switch 257. As particularly shown, the arm 262 carries a cam projection 263 which is operative against an extension of the contact 259 which lies in the circular path of movement of the cam projection 263, the latter being suitably insulated from the arm, or itself being of electrically non-conducting material.

Mutually spaced brackets 263 and 264 and 265 extend upwardly from the base plate 245 and provide bearings which rotatively carry a shaft 266 in alignment with the shaft 252 and for its axial shifting. The mutually opposed extremities of the shafts 252 and 266 between the brackets 255 and 263 carry clutch plates 267 and 268 respectively for mutual engagement for the driving of the shaft 266 from the shaft 252. An helical spring 269 encircles the shaft 266 between the brackets 263 and 264 and is constantly operative between the bracket 263 and a collar 271 fixed on the shaft to yieldingly effect a released disposal of the clutch plate 268. The collar 271 may engage the bracket 264 to limit the clutch-disengaging movement of the shaft 266.

The end of the shaft 266 beyond the bracket 265 is provided with a bearing socket 272 for receiving the extremity of a pin 273 carried by an arm 274 which is pivoted for its swinging in a plane including the shaft axis and extends transversely of the shaft opposite said end thereof. As illustrated, the arm 274 is pivoted at an end thereof to the base 245 for movement in a plane parallel to said base, and provides the shaft-engaging pin 273 intermediately of its length.

65 A lateral extension 264' of the bracket 264 carries an electromagnet 275 opposite the free end of the arm 274 with its axis in the plane of movement of the arm and transverse to the arm, and with the outer end of the armature 275' of the electromagnet pivotally engaged with the arm end. The armature 275' is arranged to be extended from the electromagnet coil 275'' while the shaft 266 is disposed to disengage the clutch 267-268, and an energizing of the electromagnet is arranged to swing the arm 274 to axially shift

the shaft 266 against the resistance of the spring 269 and so engage the clutch for effecting a rotation of the shaft 266 with and from the shaft 252.

When the arm 274 is displaced by the action of the electromagnet 275 to engage the clutch, it is arranged to simultaneously close an otherwise open switch 276 which controls the output circuit for the unit. As shown, said arm carries a contact 277 for engaging a fixed contact 278 mounted on the base 245, each of said contacts being electrically insulated from the elements which support them. In the present instance, and as indicated in Figure 22, the switch 276 controls the input to a suitable radio transmitting unit as does the switch 31 of the sending unit 21.

It will now be noted that the rotation of the shaft 266 is arranged to effect a longitudinal feeding movement of the perforated tape 242 in a suitable guideway which includes a support member 279 providing a trough-like guideway portion in which the tape may be longitudinally moved and guided. The member 279 supports a switch 281 which comprises a pair of mutually parallel spring arms 282 and 283 having contacts 282' and 283' for engagement to close a circuit including the switch. The free ends of the arms 282 and 283 extend over the center of the guideway of the member 279 in generally parallel relation thereto and to each other, and the lower arm 283 has a conical pin or finger 284 depending transversely therefrom to ride on the tape or engage a hole 243 therein. When the finger 284 rides on the tape, the switch is arranged to be closed at the contacts 282' and 283' thereof, and when the finger 284 engages in a tape hole 243, the switch is open. If desired, a slight depression may be provided in the member 279 in the line of movement of the finger 284 whereby the movement of the finger between switch-closing and switch-opening positions thereof may exceed the thickness of the tape.

For moving the tape beneath the switch control finger 284, the tape is passed between feed rollers 285 and 286 which are located in advance of the finger whereby the tape may be tensed between the rollers and fingers as it is pulled beneath the finger by the roller, the tapering of the finger tip being such as to provide for a wedged lifting of the finger from a tape perforation which it engages. The roller 285 is mounted on the shaft 266 between the brackets 264 and 265, and the roller 286 is carried by a rock-frame 287 pivoted to and between said brackets eccentrically of the roller axis. At the opposite ends thereof the roller 285 is provided with toothed friction flanges 288 for gripping the tape sides against the roller 286, and the tape-engaging face of the roller 286 is a true cylinder. A spring 289 is normally operative against the frame 287 to resiliently and yieldingly urge the roller 286 toward the roller 285, while gears 291 and 292 at corresponding roller ends are constantly engaged to insure a synchronized functioning of the rollers as a tape-feeding means. The frame 287 may be manually depressed to lower the roller 286 to an inoperative position during an adjusting or inserting or removing of the tape.

By particular reference to the diagram of Figure 22, it will now be noted that the electromagnet coil 275' is included in each of two circuits which include electrically parallel branches respectively including the switch 257

and the switch 281. As shown, a wire 293 connects the power wire 249 with one terminal of the coil 275', wires 294 and 295 connect the other coil terminal with terminals of the switches 257 and 281 respectively, and a wire 296 connects the other switch terminals with the power wire 248.

With the motor 246 operating the shaft 252 at a constant and predetermined rotative speed, the clutch 267-268 disengaged, and the finger 284 of the switch 281 engaged in a tape hole 243 whereby the switch is then open, the continued rotation of the shaft 252 will effect a closing of the switch 257 through the action of the arm 262 thereon and so energize the coil 251 to cause an engagement of the clutch and an advance movement of the tape 242 laterally from beneath the finger 284 and so lift the latter to close the switch 281. The closing of the switch 257 is arranged to endure long enough to insure the closing of the switch 281 before the switch 257 may open, and thus maintain the energizing of the electromagnet until the finger 284 engages the succeeding tape hole 243. In this manner, the circuit of the switch 276 is arranged to be held closed for a time period which endures from the closing of the switch 257 through the closing and reopening of the switch 281, and it will thus be understood that the relative spacing of successive holes 243 of the tape alone determines the length of impulse provided by the circuit of the switch 276.

A suitable means is provided for perforating a tape for use in the unit 241 to create endurance-differentiated impulses in the described manner. As is shown in Figures 28 to 31 inclusive, a tape-perforating unit 301 is provided for the purpose, said unit being arranged for manual operation in the manner of a typewriter. The mechanism of the unit 301 is mounted on the pair of side plates 302 and 303 which extend upwardly from a base plate 304 to which they are fixed in mutually parallel relation. At an end thereof which extends forwardly beyond the base plate 304, and at its outer face, the plate 302 mounts a spool 305 which is arranged to carry a roll of the unperforated tape 242 for its advancement and perforating in the unit by reason of the selective actuation of the keys 306 of the unit.

The keys 306 are provided at the free forward ends of keybars 307 which at their rearward ends pivotally engage a common pivot shaft 308 fixed in and between the plates 302 and 303. The arrangement of the keys 306 may be any suitable one at the keyboard portion of the unit; as shown, the keys are arranged in three lines which are mutually stepped down toward the unit front, and the keys are equally spaced in their lines, all in a usual arrangement for typewriter keyboards. Fixed cross-bars 309 and 311 at the front of the frame are operative to provide stops to limit the possible angular oscillation of the various keybars between raised and depressed positions thereof. As shown, the bar 309 overlies the keybars at a line adjacent the rear line of the keys, and individual tension springs 312 are constantly operative between the keybars and an upper crossbar 313 of the frame to yieldingly urge and normally maintain a raised positioning of the keybars against the stop bar 309. As shown, the springs 312 are secured to the bar 313 by means of eye-bolts 314 whereby the spring tension may be adjusted as desired.

A shaft 316 is journaled in and between the plates 302 and 303 and extends beyond the plate 302. The shaft 316 carries a set of ratchet wheels

317 of like size fixed thereon, there being a wheel 317 for each keybar. As particularly shown, the keybars 307 are operative in planes which lie between adjacent those of the corresponding wheels 317, and the keybar portions opposite the shaft are offset upwardly around the shaft and the ratchet wheel hubs to permit a full depression of the key. A pawl 318 is pivoted on each keybar for operation against a corresponding ratchet wheel 317 while the keybar makes a down or displacement stroke when its key is pressed down by a person's finger or mechanically. A leaf spring 319 mounted on the keybar constantly urges the dogging tooth of the pawl against the teeth of the ratchet wheel to insure the desired operation of the pawl tooth.

It will now be noted that the extending end of the shaft 316 carries a tape-feeding roller 321 in the plane of the tape extending from the spool 305, said roller having toothed end flanges 322 for engaging the side edge portions of the tape engaged between it and a complementary feed roller 323. The roller 323 is carried by a rock-frame 324 pivoted on the plate 302, and a spring 325 is constantly reactive between the rock frame and an anchorage on the plate 302 to resiliently and yieldingly retain the roller against the tape, while permitting a downward swinging of the roller to provide for a removal or adjustment of the tape between it and the roller 321. Gears 326 and 327 on the feed rollers 321 and 323 are provided for meshing when the rollers engage the tape between them. Rearwardly of the feed roller assembly, the unrolled tape portion passes over a plate or block 328 fixedly mounted on the plate 302 and providing a supporting slideway for the tape thereat, it being noted that the tape portion between the block 328 and a pair of idler rollers 329 mounted on the plate 302 between the feed rollers and spool is arranged to be flat.

An arm 331 extends forwardly from the shaft 332 which is journalled in and between the plates 302 and 303 rearwardly of the block 328, said arm overlying the block 328 and engaging a cutting die punch 333 which is slidably mounted on the plate 302 for coaction with a complementary die hole 334 in the block to perforate the tape for providing the holes 243 therein, when the arm is swung down from a normally raised position thereof. The arm 331 and shaft 332 comprise parts of a rock-frame which includes a second arm 335 fixed on the shaft adjacent the plate 303 and a bar 336 connecting the forward ends of the arms 331 and 335 to provide a rigid frame for swinging as a unit about the axis of the shaft.

The bar 336 is parallel to the shaft 332, extends freely through an arcuate slot 337 in the plate 302, and underlies the keybars 307 just rearwardly of the stop bar 311 at such a distance below the keybars that the depression of any keybar will engage the bar 336 to rock the frame and effect a perforation of the tape by the punch as the depression stroke of the keybar is completed. A compression spring 338 constantly urges the punch 333 upwardly against the arm 331 to normally support the arm and rock-frame in raised position.

Since the spacing of each pair of successive tape perforations 243 is designed to represent only one particular key of the unit 301 with a different spacing provided for each key, means are provided to effect appropriate spacings of successive perforations in accordance with the key struck, said means being operative to adjustably control the permitted angle of displace-

ment of the keybars and so control the working strokes of the various pawls with respect to the ratchet wheels 317. As is particularly shown, stop pins 339 are threadedly engaged in the stop bar 311 to extend upwardly therefrom with their heads in the planes of movement of the overlying keybar portions whereby the downward stroke of each keybar may be adjustably limited. Pins 341 are threadedly engaged in the bar 336 in the path of movement of the keybars above them to extend toward the keybars to adjusted degrees. In setting the present unit for perforating a tape, the pins 339 would be individually set to provide for the advance of the tape at each depression 15 of the keybar through a distance corresponding to that key, and the corresponding pin 341 would be set to cause a punching of a hole in the tape just as the keybar completes its permitted working stroke. Since the point of punching is beyond the feed rollers for the tape, the tape may buckle slightly during the actual punching of the hole, this being harmless since the pins 341 would be set to provide for the same amount of buckling for all punching operations. Since the pins 339 may be variably set with respect to their keys, coding may be effected by setting them in various arrangements with respect to the keys.

A spring 342 is frictionally operative against the tape spool 305 to prevent its free rotation, and the feed roller assembly 321-323 secures the tape against advancement except when a keybar is being depressed. With the present arrangement, it will be understood that the distance between successive perforations of the perforated tape portion will correspond to the key which was depressed to produce the last perforation of a pair, whereby the use of the tape in the unit 241 may control the latter in the described manner. And it will be further noted that the actual difference in the distances between pairs of perforations representing different keys must be a whole number multiple of the tape-advancing distance represented by one tooth of the ratchet wheels 317, the pitch distance of the ratchet wheel teeth being made small enough to provide for the range of perforation spacings to be made.

The perforations 244 for reference or checking purposes may be provided at the option of the operator preparing the tape by a hand punch 50 which is operative at the punch block 328 and comprises a punch pin 343 slidably mounted on the plate 302 in upright position and provided with a head 344 for striking with a hand. A compression spring 345 is constantly operative 55 between the head 344 and the plate 302 to urge a raised and inoperative positioning of the punch 343, said punch pin being actuated alternately with the keys and when desired, to provide the perforations 244 at a tape edge, said perforations being equally spaced longitudinally of the tape from the tape holes 243 which immediately follow them.

Means are preferably provided to prevent the simultaneous striking by an operator's finger of more than one punch-operating key 306 of the tape-punching unit 301. As is shown in Figures 28 to 31, said means comprises a plate element 346 fixed to the upper frame portion and extending forwardly to overlie the keyboard of the unit. The plate 346 for use with the present keyboard is of stepped form to provide portions which are each arranged to closely overlie the raised keys in the lines thereof, and are provided opposite the keys with circular perforations 347 which are preferably coaxial with the keys and of slightly

less diameter than the keys. The arrangement is such that an operator's finger tip may engage but one key at a time, whereby to avoid the depression of two keys at the same time and the provision of the wrong hole spacing on the tape when an operator's finger is to be applied to a given key. It will be noted that the present device is adaptable and applicable to keyboards generally, and including the keyboard of the unit 21, and avoids any necessity for an undue spreading of the keys of a keyboard as an alternative means for accomplishing the purpose of the device.

It will now be noted that sending unit 21 (Figures 1 to 11) and the sending unit 241 (Figures 15 to 27) may be selectively used with either the receiving unit 121 (Figures 12 to 20) or the receiving unit 219 (Figure 21). Figure 32 diagrammatically indicates certain possibilities in the use of the various units with or without a printing machine P and cipher machines C and C', and for either wire or radio transmission of the control impulse. As shown, the sending units 21 and 241 are arranged for optional connection, through a double-throw switch S, with circuits including an electric battery 101 and either the radio broadcasting unit 102 or conductors W for the transmission of their output impulses to either one of the receiving units 121 or 219 at a receiving station, radio transmission 30 being obviously necessary for a moving or movable receiving station at which the printing machine or other controlled mechanism is located. The transmitted impulses are received at a double-throw switch S through the wires W or 35 the radio receiving unit 103, and a second switch S may be set to energize either the receiver 121 or the receiver 219 to translate the transmitted impulses into working impulses.

The sending unit 21 may be operated by hand, 40 or its key-bars may be controlled by the action of the electromagnets of a key-operating unit K which are selectively engaged by the actuation of a cipher machine C which is set for coding. The sending unit 241, it will be recalled, is arranged 45 for actuation by a prepared tape 242 which may be fed through the mechanism in the described manner.

The output circuits of the receivers 121 or 219 may energize an electric typewriter P-K through connections provided by a multi-conductor cable D. If the cipher machine C is connected for operating the sender 21, the output 55 circuits of the receiver 121 may energize the decoding unit C' through connections provided by a cable E, said decoding unit then being connected with the printer P by the cable D, as is indicated in dotted lines in Figure 32. The extra circuit for a lamp 216 or some other device will be energized in either case, and also when the unit 219 is energized. The remaining output circuits of the unit 219 may operate a printer, through or without a decoder, or any other mechanism suitable to be controlled thereby, as 60 has previously been noted.

From the foregoing description, taken in connection with the accompanying drawings, the advantages of the control system of my invention will be readily understood by those skilled in the art to which the invention appertains. While I 70 have described the principles of operation, together with devices which I now consider to be preferred embodiments thereof, I desire to have it understood that the showing is primarily illustrative, and that such changes may be made, 75

when desired, as fall within the scope of the following claims.

What is claimed is:

1. In a remote control system, a normally quiescent sending mechanism arranged to provide electric impulses of different lengths in an unbranched output circuit thereof and for translation at a receiving station into different functions and including a normally open switch for said output circuit, a rotary member, means selectively coercive between the member and switch to determine different periods of closing for the switch with respect to the rotation period of the member, and means for selective actuation to cause the rotation of the member to provide a said impulse of predetermined duration.

2. In a remote control system, normally quiescent sending and receiving mechanisms, means of the sending mechanism for operation to selectively provide continuous electric impulses of different and automatically fixed duration for each of a plurality of functions to be performed, said means comprising a longitudinally perforated tape having different spacings of its perforations each corresponding to the different function, means operative to longitudinally advance the tape at a fixed rate, a switch means controlled by the perforations of the advancing tape to provide the impulses in the output circuit of the sending mechanism, a rotary commutator switch of the receiving mechanism controlling function circuits of the receiving mechanism, and means whereby an impulse from the sending mechanism is arranged to cause the rotation of the commutator switch to selectively close the appropriate function circuit through said switch.

3. In a remote control system having receiving and sending mechanisms, means of the sending mechanism for actuation to selectively provide mutually differentiated and single electric impulses corresponding to each one of a plurality of functions to be performed, electric function circuits of the receiving mechanism corresponding to the different said functions and including a relay for energizing to close a secondary circuit, means automatically operative to temporarily close a said function circuit by and upon the termination of a received said impulse corresponding thereto, and means automatically operative to maintain the closed condition of said secondary circuit after the means for closing the function circuit becomes inoperative.

4. In a remote control system having sending and receiving mechanisms, means of the sending mechanism for actuation to selectively provide a single electric impulse for each one of a plurality of functions to be performed, said impulses being of different time duration, electric function circuits of the receiving mechanism corresponding to the different functions, means automatically operative to temporarily close a function circuit by and upon the termination of a received said impulse corresponding thereto, and means automatically operative to maintain the closed condition of the function circuit after the means for closing the function circuit becomes inoperative.

5. A system in accordance with claim 4 wherein the last means is operative only for a predetermined time interval.

6. A system in accordance with claim 4 wherein the operativeness of the last means with respect to the function circuit is arranged to automatically cease for all of said circuits at the end of

like time intervals from the beginning of the actuating impulse.

7. In a remote control system, electric sending and receiving mechanisms connected by a single circuit, a normally open sending switch in the said circuit, a closing means for said switch, a rotary member of the sending mechanism for rotation at a predetermined rotary speed and comprising a unitary assembly of cam elements, means selectively cooperative between the cam elements and the switch-closing means to effect a closing of the switch for mutually different periods all less than the period of rotation of the cam elements, and means to selectively render a cam element operative to close the switch to produce an impulse of predetermined duration in the circuit.

8. In a remote control system, normally quies-

cent sending and receiving mechanism, means of the sending mechanism for operation to selectively provide continuous electric output impulses of different and automatically fixed duration for each of a plurality of functions to be performed, said means comprising a longitudinally perforated tape having different spacings of its perforations each corresponding to different functions, means operative to longitudinally advance the tape at a fixed rate, a switch means controlled by the perforations of the advancing tape to provide the impulses in the output circuit of the sending mechanism, and means of the receiving mechanism to automatically translate a received said impulse for effecting the performance of the function which it represents.

EDWARD H. HEBERN.
